ANGLE FRAMER

Walter E. Holt, Box 1814, Loris, S.C.
Filed Jan. 19, 1961, Ser. No. 83,745
7 Claims. (Cl. 33—91)

This invention relates to a tool, and more particularly to a tool for facilitating the measuring, laying-off and or marking of work such as rafters.

The primary object of the invention is to provide an angle framer or tool which is adapted to be used by carpenters or the like so as to facilitate the laying-off of rafters and various bevels that are usually required in building or various types of construction work.

A further object of the invention is to provide an angle framer of the type stated that is adapted to be conveniently and efficiently used for accurately laying out lines at different angles and planes at different positions as for example when roofing timbers, rafters or the like are being marked off preparatory to sawing the same or cutting such work pieces.

Still another object is to provide such an angle framer or tool that is economical to manufacture and efficient in operation and which is rugged in structure and fool-proof in use.

These and other objects of the invention will become apparent from a reading of the following specification and claims, together with the accompanying drawings, wherein like parts are referred to and indicated by like reference characters and wherein:

FIGURE 1 is a plan view of the angle framer of the present invention, with parts broken away and in section.

FIGURE 2 is a fragmentary sectional view showing certain constructional details of the cam locking mechanism and its associated parts.

FIGURE 3 is a sectional view taken on the line 3—3 of FIGURE 1.

FIGURE 4 is a fragmentary bottom plan view showing the rafter table on the back side of the tool.

FIGURE 5 is a fragmentary perspective view showing the parts separated or disassembled, and with parts broken away and in section.

FIGURE 6 is a sectional view taken on the line 6—6 of FIGURE 5.

FIGURE 7 is a fragmentary perspective view showing a portion of one of the movable hands.

Referring in detail to the drawings, the numeral 10 indicates the tool or angle framer of the present invention which is shown to comprise a bar that is indicated generally by the numeral 11, and the bar 11 includes a main body portion 12 of rectangular formation, FIGURE 1. The numerals 13 and 14 indicate opposite sides or surfaces of the bar 11, and the bar 11 is provided with longitudinally extending spaced parallel straight side edges 15 and 16, FIGURE 4. There is also provided in the bar finger engaging indentations or recesses 17 and 18 for a purpose to be later described, FIGURE 1.

Arranged contiguous to one end of the bar 11 and secured thereto or formed integral therewith is a support member 24 which is provided with a tapered upper surface 19 as well as an inner arcuate surface 20, and there is provided in the inner edge portion of the support member 24 a plurality of spaced apart indentations or apertures 21. The numeral 22 indicates indicia or scale mark-

2

ings on a tapered surface 19 which is suitably calibrated or aligned with the apertures 21. The support member 24 may be secured in place to the adjacent end portion of the bar 11 as for example by means of screws 25.

5 The bar 11 is provided with a cutaway portion 26 adjacent one end thereof and a plate 27 is seated in and secured in the cutaway portion 26. The numeral 28 indicates a stud or pin which includes an enlarged head 29 as well as a stem portion 30, FIGURE 3, and the stud 28 is affixed to the bar 11 and has its stem portion 30 projecting through the plate 27 as shown in the drawings. The stud 28 is provided with an outer externally threaded portion 31 as well as an inner hollow threaded section 32. As shown in FIGURE 5 for example the bar 11 has on one side thereof a recessed or cutaway portion 33 which is shaped to define or provide edge portions 34 and 35.

10 The numeral 36 indicates a first movable hand or blade which comprises a flat portion 37 that has a generally tapering formation which is defined between straight edges 20 38 and 39 that are arranged angularly with respect to each other, and one end of the hand 36 is slightly enlarged as at 40, and this end portion 40 is provided with a large circular opening 41.

15 There is further provided a second movable hand or blade which is indicated generally by the numeral 42, and the hand 42 includes a main flat portion or section 43 having a somewhat tapered formation defined between straight edges 44 and 45, and the second hand 42 is further provided with an enlarged generally arcuate or rounded shoulder 46 that has a plurality of spaced apart notches 47 thereon, FIGURE 7. Indicia 48 is arranged on the shoulder 46 as for example as shown in FIGURE 1. The second hand 42 is also provided with a pointer 49 on one end thereof, and the pointer 49 is adapted to 20 selectively engage in the apertures 21 in the support member 24.

25 As shown in the drawings, a knurled pressure element 52 is adapted to be arranged in threaded engagement with the threaded portion 31 of the stud 28, and a locking element 53 is also provided, the locking element 53 including a knurled portion 54 as well as a reduced diameter threaded shank 55 which is adapted to threadedly engage the threaded section 32 of the stud 28 so as to help maintain the parts in their proper assembled relationship.

30 Secured or formed integral with one side of the second hand 42 is a circular base portion 50, and the base portion 50 and hand 42 are provided with a slot 51 for the projection therethrough of the stem portion 30 of the stud 28. The base portion 50 is rotatably received in the opening 41 of the hand 36, as for example as shown in FIGURE 3.

35 The angle framer of the present invention further embodies a generally circular rotatable disc which is indicated generally by the numeral 57, and the disc 57 is provided with a central opening 58 for the projection therethrough of the stem portion 30 of the stud 28. The disc 57 is provided with a finger engaging lug 59 thereon for facilitating the manual turning or rotation of the disc 57, and the numeral 60 indicates a pin which extends upwardly from the hand 42 and which is secured thereto or formed integral therewith. As shown in FIGURE 2 for example, a portion of the disc 57 is recessed or cutaway adjacent the outer periphery thereof as at 61 so as to define a locking cam surface 62 for coaction with the

pin 56, and an outer peripheral portion of the disc 57 may be tapered or beveled as at 63.

Attention is directed to FIGURE 1 of the drawings, wherein the numeral 64 indicates a pin member which is suitably affixed to the bar 11, and the pin member 64 is adapted to selectively project through or engage a small opening 65 in the hand 42 whereby the hand 42 can be selectively maintained in a stationary position contiguous to the bar 11.

The numeral 66 indicates a manually operable latch mechanism which comprises a spring member 67 that has one end secured as at 68 to the hand 36, and a bracket 69 straddles or extends over a portion of the spring member 67, and the bracket 69 is fastened to the hand 36 as for example by means of rivets or securing elements 70. The latch 66 further includes a finger piece 71 which includes a portion 72 that is provided with a slot 73 for the projection therethrough of a fastener or securing element 74, and the finger piece 71 further includes offset portions 75 and 76 as well as a pointer 77, and the pointer 77 is adapted to engage and coat with the notches 47 of the shoulder 46 of the hand 42.

In FIGURE 1 the numeral 78 indicates a work piece which is adapted to be scribed or marked or measured as for example when using the tool 10 of the present invention.

As shown in FIGURE 4, indicia as indicated by the numeral 79 is adapted to be arranged on the under or back side of the bar 11, and this indicia 79 may consist of rafter tables for providing a handy reference to pitch or the like.

From the foregoing, it is apparent that there has been provided a tool which is especially suitable as an angle framer, and the tool of the present invention can be used for accurately and readily laying off of rafters and various polygonal bevels usually required in building, and the tool of the present invention is especially suitable for use by carpenters or other craftsmen or workmen. The tool includes a pair of blades or movable hands which can be readily set and fixed at any desired angle with respect to each other so that various angles can be scribed or marked on a work piece such as the member 78.

Basically the tool of the present invention consists of the bar 11 which has the pair of blades 36 and 42 adjustably connected thereto as for example by means of the stud 28 and associated parts, and in addition there is provided the latch mechanism 66 as previously described. The following is given as a description of the use or movement of the parts as for example when the tool is being operated. First, the locking disc or washer 57 on the stub 28 is released by manually rotating the disc 57, and this rotation of the disc 57 is facilitated due to the provision of the enlargement or lug 59 which can be conveniently engaged by the user's finger and by moving the disc 57 in such a manner that the cam surface 62 moves out of engagement with the pin 56, the disc 57 will be unlocked or released. Then, the longer hand 42 is raised slightly, as for example the finger of the user may be engaged in the indentation 17 so as to slightly elevate the end portion of the hand 42 in order to free the opening 65 from the pin 64, and the hand 42 can be pulled down with a slight pressure so as to release the pointed end 49 from the particular opening or aperture 21 at the point 49 is in, and then the hand 42 is set on any desired pitch. Thus, the indicia 22 is provided with the scale markings or indicia thereon that indicates pitch, and the apertures 21 are spaced to coincide or coat with these various pitch markings 22 so that by positioning the point 49 at a particular aperture 21, the hand 42 can be set at the desired pitch. The tapered surface 19 is provided so as to facilitate the reading or visual observation of the indicia 22 by the

carpenter or other person using the tool. After the hand 42 has been set at the desired pitch, the disc 57 is locked as for example by manually rotating the disc 57 by supplying finger pressure to the lug 59 so that the cam surface 62 moves into wedging engagement with the pin 56, as for example as shown in FIGURE 1. The slot 51 in the hand 42 provides sufficient clearance so that the stud stem portion 30 can extend through this slot 51, whereby the hand 42 can be pulled on in order to permit the pointer 49 to move downward out of engagement with a particular aperture 21, as for example when the hand 42 is being shifted in position, and after the hand 42 has been moved to the desired location, the hand 42 can be pushed forward in order to engage the pointer 49 in the desired aperture 21.

After the locking disc 57 has been tightened, the latch 66 is manually actuated, and to actuate the latch 66, it is only necessary to press down on the portion 76 of the finger piece 71, and this causes the spring member 67 to bend or flex upwardly since the spring member 67 is only fastened in place at the point 68. This upward flexing of the spring member 67 is accompanied by a pivotal or rocking movement of the finger piece 71, as for example the finger piece can move from the solid line position of FIGURE 6 to the dotted line position of FIGURE 6 whereby the pointer 77 of the finger piece will move upward out of engagement with a particular notch 47 in the shoulder 46, and with the pointer 77 out of engagement with the notch, the short hand 36 can be pivoted about an axis extending through the stud 28 so that the hand 36 can be set to the desired angular position such as a ninety degree angle whereby an edge of the hand 36 will be arranged at ninety degrees with respect to a corresponding edge of the hand 42 so that for example a carpenter can conveniently scribe a ninety degree angle on a work piece such as the work piece 78. After the hand 36 has been moved to the desired location, finger pressure on the portion 76 is released whereby the spring member 67 returns the latch parts to their original position, as for example the parts can return from the dotted line position shown in FIGURE 6 to the solid line position of FIGURE 6, whereby the pointer 77 will engage one of the notches 47 in the shoulder 46 to maintain the hand 36 immobile in its adjusted desired position. The indicia or markings 48 on the shoulder 46 are arranged to provide an accurate means of setting the hand 36 on a particular angle so that for example an octagonal, hexagonal, ninety degree mark or cut or the like can be readily accomplished, and after the hand 36 has been set, the tool is ready for use.

The tool can be readily disassembled, and to disassemble the parts of the tool it is only necessary to unscrew the securing element 53 from the stud 28, and then unscrew the pressure element 52 from the stud, and then the hand 42 can be pulled downward slightly in order to free the pointer 49 from the apertures 21 and this hand 42 can be lifted off and then the hand 36 can be removed or lifted off of the bar. The hand 36 includes the enlarged opening 41 which rotatably receives therein the circular base portion 50 of the hand 42 and this construction permits relative movement between the pair of hands 36 and 42 so that the hand 36 can be set for the desired angle relative to the hand 42, after the hand 42 has been set as previously described, and the provision of the coating base portion 50 and opening 41 serves to insure that the hand 36 will be maintained in its proper aligned position regardless of its adjusted location.

The tool is further provided with the length scale of various pitches on the stock or handle as for example as indicated by the numeral 79, and in addition the tool of the present invention provides for one hand setting off of the movable hand on degrees, registering from the movable hand and also registering from the stock or handle. Thus, the present invention includes the two

hands that set on degrees off each other and also off of the degrees from the main stock or handle so that the tool of the present invention is a multiple degree register or indicator for angle cuts. The table 79 functions as a rafter length solvent table, and the tool of the present invention is adapted to be used as a multiple angle square. The hands 36 and 42 are adapted to fall back on top of the handle or bar 11, and the hands are attached to the stud or pin 28 by means of the slot 51 in the one hand 42, and no screws or nuts are required to fasten the hands in a working position. Each of the apertures 21 represents a pitch and they run from a 1 x 12 to a 12 x 12 pitch. The long hand 42 that has the slot 51, also has a needle shaped point 49 which can be slipped in any of the various pitch apertures 21 and with the pointer 49 in an aperture 21, the hand 42 will be set to a pitch as indicated on the scale 22.

With further reference to the disc or washer 57, this can be turned until it presses against the pin 56 so that the hand can be locked in position ready to be used. Thus, the disc 57 provides a locking means for the long hand 42. Relative to the short hand 36, the short hand 36 can be set at right angles to the long hand 42, or else the short hand 36 can be set for octagon or hexagon cuts, and the various notches 47 on the shoulder 46 are spaced to correspond to such hexagon, octagon cuts or the like. The short hand 36 is set or held in position by means of the spring latch mechanism 66, and the short hand 36 can be set at right angles with respect to the long hand, or right angles with respect to the stock or bar 11. It is to be noted that the short hand 36 can be set at right angles with respect to the long hand 42 regardless at what pitch the long hand is set on, but the long hand has to be either set on a 12 x 12 pitch or closed on the handle bar 11 before the short hand 36 can be set at right angles to the handle bar 11. The hands are made so that when scribed on the top of the hands, the user gets the main rafter cut, when scribed on the bottom of the hands, the king or volley or jack rafter cut is obtained.

Minor changes in shape, size and rearrangement of details coming within the field of invention claimed may be resorted to in actual practice, if desired.

What is claimed is:

1. In an angle framer, a bar having a support member on one end thereof and said support member being provided with indicia thereon, there being a plurality of spaced apart apertures in the inner portion of said support member, a stud affixed to said bar, a first movable hand provided with a circular opening for the projection therethrough of said stud, a second moveable hand having a circular base portion rotatable in the opening in said first hand, there being a slot in said base portion and second hand for the projection therethrough of said stud, an arcuate shoulder on said second hand and said shoulder having indicia thereon, a pointer on said second hand for selectively engaging the apertures in the support member, and cam locking means operatively connected to said second hand.

2. The structure as defined in claim 1 wherein said cam locking means comprises a rotary disc having a cam surface thereon, and a pin for coaction with said cam surface.

3. The structure as defined in claim 1 and further including a pressure element and locking element arranged in threaded engagement with said stud.

4. In an angle framer, a bar having a support member on one end thereof and said support member being provided with indicia thereon, there being a plurality of spaced apart apertures in the inner portion of said support member, a stud affixed to said bar, a first movable hand provided with a circular opening for the projection therethrough of said stud, a second moveable hand having a circular base portion rotatable in the opening in said first hand, there being a slot in said base portion and second hand for the projection therethrough of said stud, 75

an arcuate shoulder on said second hand and said shoulder having indicia thereon, a pointer on said second hand for selectively engaging the apertures in the support member, and cam locking means operatively connected to said second hand, said cam locking means comprising a rotary disc having a cam surface thereon, a pin on said second hand for engagement with said cam surface, a pressure element and locking element arranged in threaded engagement with said stud, and a spring latch connected to said first hand, there being a plurality of spaced apart notches in the shoulder of said second hand, for coaction with said spring latch.

5. An angle framer comprising a bar including a main body portion of rectangular formation, a support member connected to one end of said bar, said support member including an upper tapered surface and an inner arcuate surface, indicia on the upper surface of said support member, there being a plurality of spaced apart apertures in the inner portion of said support member and said apertures being aligned with said indicia, a stud mounted in said bar and said stud including an outer externally threaded portion and an inner hollow threaded section, there being a recess in one side of said bar, a first movable hand adapted to selectively seat in said recess, and 20 said hand including a flat portion having longitudinally extending straight side edges, one end of said hand being enlarged and being provided with a circular opening; a second movable hand including a main flat portion, an arcuate shoulder on one end of said second hand indicia on said shoulder, a circular base portion on the inner surface of said second hand and said base portion being rotatably received in the opening in the first hand, there being a slot in said base portion and shoulder for the projection therethrough of said stud, a pointer on said 25 second hand for selectively engaging the apertures in said support member, a knurled pressure element arranged in threaded engagement with the externally threaded projecting portion of said stud, a locking element including a reduced diameter threaded shank arranged in threaded engagement with the inner hollow threaded section of said stud, a pin extending upwardly from said second hand, a rotary disc provided with a central opening for the projection therethrough of said stud, a finger engaging lug on said disc, there being a recessed portion in the outer periphery of said disc defining a locking cam surface for coaction with said pin.

6. An angle framer comprising a bar including a main body portion of rectangular formation, a support member connected to one end of said bar, said support member including an upper tapered surface and an inner arcuate surface, indicia on the upper surface of said support member, there being a plurality of spaced apart apertures in the inner portion of said support member and said apertures being aligned with said indicia, a stud mounted in said bar and said stud including an outer externally threaded portion and an inner hollow threaded section, there being a recess in one side of said bar, a first movable hand adapted to selectively seat in said recess, and said hand including a flat portion having longitudinally extending straight side edges, one end of said hand being enlarged and being provided with a circular opening; a second movable hand including a main flat portion, an arcuate shoulder on one end of said second hand, indicia on said shoulder, a circular base portion on the inner surface of said second hand and said base portion being rotatably received in the opening in the first hand, there being a slot in said base portion and shoulder for the projection therethrough of said stud, a pointer on said second hand for selectively engaging the apertures in said support member, a knurled pressure element arranged in threaded engagement with the externally threaded projecting portion of said stud, a locking element including a reduced diameter threaded shank arranged in threaded engagement with the inner hollow threaded section of said stud, a pin extending upwardly from said

second hand, a rotary disc provided with a central opening for the projection therethrough of said stud, a finger engaging lug on said disc, there being a recessed portion in the outer periphery of said disc defining a locking cam surface for coaction with said pin, and a manually operable latch embodying a spring member secured to said first hand, a bracket straddling said spring member and affixed to said first hand, a finger piece connected to said spring member and said finger piece including offset portions and said finger piece being provided with a pointer, there being a plurality of notches in the shoulder of the second hand for selectively receiving the pointer of said finger piece.

7. The structure as defined in claim 6 and further including a pin member extending upwardly from said bar, there being a small opening in said second hand for at times engaging and receiving said pin member.
